UNITED STATES PATENT OFFICE.

HARRY PAYTON, OF PROVIDENCE, RHODE ISLAND.

DESIGN FOR AN EMBLEM, BADGE, BUTTON, OR SIMILAR ARTICLE.

56,624.

Specification for Design.

Patented Nov. 16, 1920.

Application filed July 12, 1920. Serial No. 395,783. Term of patent 3½ years.

To all whom it may concern:

Be it known that I, HARRY PAYTON, a citizen of the United States, residing at the city of Providence, county of Providence, State of Rhode Island, have invented a new, original, and ornamental Design for an Emblem, Badge, Button, or Similar Article, of which the following is a specification, reference being had to the accompanying drawing, forming part thereof.

The figure is a face view of an emblem, badge, button, or similar article showing my new design which is shaded to indicate the different colors.

I claim:

The ornamental design for an emblem, badge, button, or similar article substantially as shown.

HARRY PAYTON.
